AUTOMATIC DEFROSTING CONTROL MECHANISM FOR HEAT PUMPS AND THE LIKE
John Liebermann, Columbus, and Robert E. Brooks, Worthington, Ohio, assignors to Ranco Incorporated, Columbus, Ohio, a corporation of Ohio
Filed Dec. 11, 1963, Ser. No. 329,816
5 Claims. (Cl. 200—136.3)

This invention relates to deice or defrosting controls for automatically removing ice from evaporator coils of heat pumps of the compressor-condenser-expander type refrigerating systems and particularly of such heat pump systems when they are operated in the heating phase. As is well known in the art, when outdoor temperatures are in the zone of about 50° F. and below, there is a tendency for ice to accumulate on the outdoor coil or evaporator of heat pump systems of the type mentioned when the system is on the heating cycle with an attendant reduction in heat exchange efficiency thereof. Numerous arrangements have been proposed heretofore for effecting temporary reversal of the phase of operation of the system through solenoid valve means, etc., so that the 10 iced coil acts temporarily as a condenser, and the heat therefrom quickly melts the ice. However, no completely satisfactory system has been provided for automatically controlling the initiation and termination of this deicing cycle.

It is a principal object of this invention to provide a novel time and temperature responsive switch or device control which is operative to periodically establish capability of initiating a deicing cycle for an evaporator subject to the presence of a predetermined temperature at the evaporator sufficiently low to cause accumulation of ice on the evaporator, and which control terminates the deicing cycle upon attainment of a second higher temperature at the evaporator indicative of the removal of the ice therefrom.

Another object of this invention is the provision of a deice control for refrigeration systems and comprising an electric switch having an actuator member movable between first and second operative positions for respectively initiating and terminating deice cycles, the actuator member being held between its operative positions during normal operation of the system and urged toward its deice initiating position by thermally responsive means in response to a predetermined low temperature at the evaporator, and timer operated means for blocking movement of the actuator member to its deice cycle initiating position except at predetermined intervals, whereby deice cycles are initiated by the simultaneous occurrence of the low temperature and the passage of a timed interval.

Yet another object of this invention is the provision of a deice control of the foregoing character wherein the thermally responsive means comprises a thermally expansible power element working against a primary load means for determining the predetermined low temperature at which the actuator member is moved to its deice cycle initiating position, and means for subjecting the expansible power element to an additional or secondary load upon temperature increases above normal operating temperature at the evaporator, whereby the actuator member is moved by the thermally responsive means to its deice cycle terminating position only upon the attainment of a predetermined high temperature sufficient to melt the ice at the evaporator.

Still another object of this invention is the provision of an improved time and temperature responsive deice con-

2

trol wherein the timer operated blocking means may be adjusted to select the timed intervals at which the switch actuator member will be movable to its deice cycle initiating position if icing temperatures are present at the evaporator. In a preferred embodiment, the timer operated blocking means comprises a novel cam construction including a cam rotated at a predetermined rate and having a plurality of recesses in the periphery thereof for cooperation with cam follower means to determine the passage of time intervals, and selectively positionable mask means for alternatively masking or revealing one or more of said recesses to the cam follower means so as to vary the time intervals, the mask being clutched in its selected positions for rotation with the cam.

As another object this invention aims to provide a deice control which is fail safe with regard to the thermally responsive portion thereof so that in the unlikely event of failure of the thermal power element, such as by loss of expansible fluid charge from a bellows or the like, the control device will be conditioned to both initiate and terminate the deice cycles on a purely time basis.

The invention may be further described as residing in certain novel constructions and arrangements of parts by which the foregoing objects and advantages, as well as others, are achieved, as will become apparent from the following detailed description of a presently preferred form of deicer control embodying the features of this invention.

In the accompanying sheets of drawings, forming a part 30 of this specification

FIG. 1 is a schematic illustration of a reversible heat pump system of the compressor-condenser-evaporator type including a deice control device embodying this invention;

FIG. 2 is an enlarged elevational view of the deice control device of FIG. 1, with a fragmentary showing of the evaporator coil;

FIG. 3 is a bottom view of the deice control device of FIG. 2, viewed along line 3—3 thereof;

FIG. 4 is an enlarged sectional view of the control device taken substantially along line 4—4 of FIG. 3;

FIGS. 5 and 6 are views similar to FIG. 4 but showing some parts in different operating positions, and with some parts broken away for clarity;

FIG. 7 is a fragmentary sectional view taken along line 7—7 of FIG. 4;

FIG. 8 is a sectional view taken substantially along line 8—8 of FIG. 4;

FIG. 9 is an enlarged fragmentary view of a portion 50 of the device viewed substantially along line 9—9 of FIG. 3; and

FIG. 10 is a still larger fragmentary view of the subject matter of FIG. 9 with parts in section.

Referring to FIG. 1 of the drawings, there is illustrated 55 therein a reversible heat pump system of the type advantageously employing a deice control device embodying this invention. The heat pump system comprises a compressor-condenser-evaporator circuit including a motor-compressor 10, a solenoid operated reversing valve 12, an indoor heat exchanger 18, an outdoor heat exchanger 19, and a capillary 20 providing flow restriction between the heat exchangers. The heat exchangers 18 and 19 are of conventional construction comprising coils of tubing 18a and 19a which may be provided with fins, air conducting shrouds, and the like.

The motor-compressor 10 is connected by electrical conductors 21, 22, and a suitable thermostatic switch 23 to power lines L1 and L2. The thermostatic switch 23 may be conveniently located in the space to be tempered

by the indoor heat exchanger 18, and cyclically energizes and deenergizes the motor-compressor 10 as necessary to maintain a predetermined temperature level in the tempered space. The reversing valve 12 comprises a solenoid 12a which is connected to power lines L1 and L2 by suitable conductors 24, 25, and a deice control 26 embodying this invention and described in detail hereinafter.

The reversing valve 12 is actuatable by energizing or de-energizing the solenoid 12a thereof to condition the system to provide cooling or heating respectively of the space to be tempered by the indoor heat exchanger 18. Thus, when the space is to be heated, the indoor heat exchanger 18 serves as the condenser while the outdoor heat exchanger 19 serves as the evaporator. In that phase of operation, refrigerant flow may be traced from the discharge side of a motor-compressor 10 through tube 28, reversing valve 12, tube 29, indoor heat exchanger 18, capillary 20, the outdoor heat exchanger 19 acting as the evaporator, tube 31, the reversing valve 12, and tube 32 to the intake side of the motor-compressor. Hot compressed gas from the motor compressor 10 is condensed in the heat exchanger 18, thereby giving up heat to the space to be tempered. The condensed refrigerant then passes through the capillary 20 for expansion in the heat exchanger 19 wherein the refrigerant takes on heat from air circulated over the tubing 19a thereof. During such operation the coils of tubing 19a of the outdoor heat exchanger are cooled considerably, often to temperatures below the freezing point of water. At times, such as during early morning hours when humidity is relatively high, there is a tendency for frost to collect on the coils 19a, which frost insulates the coils and reduces the heat exchange efficiency thereof.

The frost may be effectively removed by energizing the solenoid 12a to cause the valve 12 to reverse the flow of refrigerant to the heat exchangers 18 and 19 and thereby conditioning the system to effect a temporary heating of the outdoor heat exchanger 19 by hot compressed refrigerant gas coming directly from the compressor 10. To this end, the deice control device 26, embodying this invention, is operative to energize the reversing valve solenoid 12a to effect heating of the heat exchanger 19 at timed intervals if the evaporator coils 19a are at or below freezing temperature as sensed by a hub 36 forming part of the control 30 and connected therewith by a capillary tube 37, all as will be described more fully hereinafter.

Referring now to the remainder of the drawings, the deice control device 26 includes a generally rectangular sheet metal frame 41 having what will be referred to as side walls 41a and 41b, end walls 41c and 41d, and a top wall 41e, although it will be understood that the control device does not require any particular orientation in use. Mounted on the frame 41 between the side walls 41a and 41b thereof, is provided an electrical, snap acting switch 42 which includes an insulating base portion 43 conveniently secured as by lugs 43a protruding from the base portion into engagement with corresponding openings in the side walls 41a and 41b. The switch 42, which in this example is a single pole double throw switch, comprises terminals 44, 45 and 46, the terminals 45 and 46 of which form part of a control circuit for the reversing valve solenoid 12a.

Referring to FIGS. 4 and 7, the inner end of the terminal member 45 is formed into a conductor bar 47 overlying the insulating base portion 43 and having a threaded opening in which is received a screw 48 carrying a normally stationary but adjustable contact 49. A movable double contact 50 is carried on one end of a flexible switch arm 51 for snap acting movement between stationary contact 49 and another stationary contact 52 connected to the inner end of terminal 44 which is in the form of a bridge 44a. The other end of the switch arm 51 is secured to the inner end 46a of terminal 46, and the

arm is moved with a snap action by toggle means operated by movement of a pivoted actuator arm 55. The actuator arm 55 has laterally spaced bearing portions 56 pivoted on knife edged projections 57 on the inner end 46a of terminal 46 and comprises a downturned hook 55a on its free end. A toggle spring 58 extends between the hook 55a and a U-shaped toggle bar 59 disposed in a central opening of the switch arm 51 and having pivotal engagement with that arm near the free end thereof. The actuator arm 55 is biased in a clockwise direction about projections 57 under the influence of spring 58, toward a position wherein the movable contact 50 is toggled into engagement with the stationary contact 49, as shown in FIG. 5, to complete a circuit between terminals 45 and 46 for initiating a defrosting cycle. When the actuator arm 55 is rotated in a counterclockwise direction about projections 57, by means described hereinafter, the toggle mechanism snaps the contact 50 from the stationary contact 49 to the stationary contact 52, as shown in FIG. 6, to interrupt or terminate a defrosting cycle.

For reasons which will become apparent as the description proceeds, switch 42 is characterized by a substantial differential between the positions of the actuator arm 55 wherein the contact 50 is toggled between the stationary contacts. Other well known forms of switch having an appreciable differential between the operative positions of an actuator arm may be used in the practice of the invention, the switch 42 being described as a preferred example.

Movement of the actuator arm 55 to produce actuation of the switch 42 is effected in part in response to predetermined temperature conditions of the evaporator as represented by temperature responsive means, and in part in response to the passage of time as represented by a timing means described later herein. The temperature responsive means includes a temperature sensing element such as the bulb 36 which is disposed adjacent the outdoor coil 19a of a heat pump apparatus so that it senses the temperature of the air leaving the outdoor coil. The temperature sensing bulb 36 is connected by a suitable capillary tube 37 to the base 73 of an expandable power element or bellows 74. The base 73 of bellows 74 is mounted on a cup member 75 having a flange 75a secured by screws 76 to the end wall 41c of frame 41, with the bellows projecting through a window therein. The bellows 74 include an axially movable bellows post 76 for transmitting motion to a bellows lever 80, presently described. The bulb 36, capillary tube 37, and bellows 74 are charged with a suitable thermally expandable fluid, preferably a vaporizable fluid, so that the bellows post 76 is positioned in accordance with the coldest part of the fluid containing system in a manner which is well understood by those skilled in the art to which the invention pertains.

The bellows lever 80, which is preferably formed as a sheet metal stamping having a central web portion 80a and spaced parallel bearing portions 80b, is pivoted at one end between the frame side walls 41a and 41b by a pivot pin 81 extending through aligned openings in the bearing portions 80b. The bellows lever 80 has a tab 80c which is bent to form a knife edge engagement with the bellows post 76, and is biased in a counterclockwise direction as viewed in the drawings into following engagement with the bellows post by an extension spring 83. The spring 83, best illustrated in FIG. 6, has a hooked end 83a engaged in openings in the web portion 80a in the bellows lever 80. The terminal convolutions of the other end 83b of the spring 83 have engaged therein a nut 85 which threadedly receives an adjusting screw 86 extending through an opening in the top wall 41e of the control frame. The head of the screw 86 is provided with a suitable screw driver slot 87 for rotating the screw 86 to adjust the tension of the spring 83 and the loading of bellows 74. A block 90 of insulating material is mounted on a screw 91 which is threadedly received in an opening 75 in the web portion 80a of the bellows lever 80, and the

insulating block 90 is engageable with the switch actuating arm 55.

Decreases in temperature at the bulb 36 below a given temperature, will result in an appreciable contraction of the bellows 74 and rotation of the bellows lever 80 and insulator block 90 in a counterclockwise direction about the pivot pin 81 under the influence of the spring 83. Such movement tends to withdraw the block 90 from the actuator arm 55 as shown in FIG. 4. Conversely, increasing the temperature at the bulb 36 will effect an expansion of the bellows 74 and rotation of the bellows lever 80 and insulator block 90 in a clockwise direction toward the actuator arm 55 as shown in FIG. 5.

The adjustment of the screw 87 and spring 83 is such that when the bulb 36 is cooled to approximately 32° F., the bellows 74 will contract and the bellows arm 80 and insulator block 90 will be moved sufficiently in a counterclockwise direction to permit the switch actuator arm 55 to effect toggling of the movable contact 50 against the stationary contact 49 to complete a circuit between terminals 45 and 46 for initiating a deice cycle, provided a timed event occurs as described hereinafter. During the deice cycle, the coil 19a is heated to free it of ice and, as the temperature of the coil 19a and the bulb 36 increases, the bellows arm 80 and insulator block 90 move in a clockwise direction and toward actuation of the switch 42 to an open position.

In order to require a temperature appreciably above the normal operating temperature of the outdoor coil 19a to be attained before the switch 42 is actuated to an open position to terminate the deice cycle, there is provided an additional bellows loading means comprising a secondary load lever 95. The load lever 95 is conveniently formed as a sheet metal stamping including a central web portion 95a having an opening 95 (FIG. 5) through which a portion of the bellows and the block 90 and screw 91 extend, and spaced parallel side portions 95b having at one end aligned openings receiving the pivot pin 81. The free end 80d of the bellows lever 80 overlies the web portion 95a near the movable end of lever 95 which is provided with a tab 95c. The tab 95c is engaged by the hooked end 97a of a secondary load spring 97 which is connected by an adjusting screw 99 and nut 99a to a cam follower lever 98. The lever 98 comprises tabs 98a extending through a slot 41f in the side wall 41b to form a pivotal connection therewith, and a projection 98b at the other end of the lever which rides on the peripheral cam surface of a cam 100. The corners of the lever 98 engaging wall 41b are preferably provided with bearing points 98c to minimize friction, and one of the tabs 98a is provided with a bent over end 98d for retaining the tabs in the slot 41f.

The cam 100 is secured at the inner end of an adjusting shaft 101 which is rotatably journaled in the side wall 41a of the frame and is provided with a screw driver slot 101a for positioning of the shaft and cam. It will be recognized that rotation of the cam 100 in a clockwise direction, as viewed in FIGS. 2 and 4 of the drawings, will act on the cam follower lever 98 to extend the spring 97 and increase the resistance of lever 95 to rotation thereof in a clockwise direction about the pivot pin 81. The lever 95 is limited in its rotation in a counterclockwise direction about the pivot pin 81 by a stop 102 which is struck inwardly from the side wall 41b. The end portion 80d of bellows lever 80 is engageable with the web portion 95b of the load lever 95 for moving the latter away from the stop 102 as the temperature of the outdoor coil 19a is increased above normal operating temperatures during the deice cycle. The increased load thereby imposed upon the bellows 74 by the load lever 95 and its spring 97 results in a relatively high temperature being required at the coil 19a to terminate the deice cycle, whereby it is assured that all of the ice is removed. This termination temperature may be selectively determined by rotation of the cam 100 to adjust the tension of spring 97 as described above.

In order to permit the initiation of a deice cycle only when both a predetermined low temperature at bulb 36 and a predetermined time occur simultaneously, the device 26 is provided with a timer motor driven cam 110 which controls the position of a spring biased blocking lever 111 which is interposed between the cam 110 and an insulating sleeve 112 on an upturned arm portion 55b of the switch actuating lever 55. The blocking lever 111 is conveniently formed from a strip of sheet metal and has an eye 111a formed at one end which receives a pivot pin 113 by which the lever 111 is pivotally mounted between the side walls 41a and 41b of the control frame. The lever 111 is provided at the other end with a cam follower portion 111b which rides the peripheral edge or cam surface of the cam 110. The lever 111 is biased in a clockwise direction about the pin 113 into following engagement with the cam 110 by a leaf spring 114, one end of which is secured to lever 111 as by a rivet 113a, and the other end of which is engaged in an opening 115 in the control frame wall 41e. A screw 116 extends through an opening in lever 111 and is threadedly engaged in an aligned opening formed in the leaf spring 114. The screw 116 is engageable with the insulating sleeve 112 on actuator arm 55 and is adjustable to calibrate the relationship between blocking lever 111 and the actuator arm.

The cam 110 is rotated in a clockwise direction, as viewed in the drawings, by a suitable timer motor such as a synchronous electric motor 120 mounted on the side wall 41b of the control frame. Referring to FIGS. 9 and 10, the cam 110 is carried by a stepped shaft 121 having a reduced end portion 122 journaled in the side wall 41b, the cam being secured against a shoulder 123 by staking of a shoulder 124. A spur gear 126 is secured to the shaft 121 between a shoulder 127 thereof and a washer 128, the latter being held in clamping engagement with the gear 126 by staking of a shoulder 129 of the shaft. The gear 126 is in meshing engagement with a drive pinion 131 of the motor 120 which serves to rotate the shaft 121 and the cam 110 at a suitable speed such as one revolution per hour.

Assuming the cam 110 to be in the position illustrated in FIG. 4 with the cam follower portion 111b of lever 111 riding on the high cam surface 117a, the lever 111 is in a position preventing movement of the switch actuator arm 55 in a clockwise direction to initiate a deice cycle even though an icing temperature is present at bulb 36 and the bellows 74 has contracted to separate the insulator block 90 from the actuator arm sufficiently to permit actuation of the switch to a closed position.

As the cam rotates, the cam follower portion 111b of lever 111 rides onto surface 118a and drops into recess 119a, thereby permitting the actuator arm 55 to rotate to its FIG. 5 position, causing the contact 50 to engage contact 49 and initiate a deice cycle. Continued rotation of the cam 110 returns the cam follower portion to surface 118a, but the accompanying rotation of actuator arm 55 in the counterclockwise direction is insufficient to overcome the above mentioned differential between operative positions thereof, and the deice cycle continues.

As the temperature of coil 19a and bulb 36 rises, the lever 80 is rotated in a clockwise direction and the end portion 80d thereof picks up the secondary load lever 95 as shown in FIG. 5. During this movement the block 90 engages and rotates the arm 55 in a counterclockwise direction until the maximum desired temperature of coil 19a is reached and, as shown in FIG. 6, the switch 42 is actuated to an open condition terminating the deice cycle. Thereafter, the evaporator returns to its normal operating temperature, in which condition the bellows contracts an amount less than that required to withdraw block 90 from arm 55 to a position permitting actuation of the switch even if one of the cam recesses 119a, 119b passes under the cam follower portion 111b.

Of course, if an icing temperature occurs at the coil 19a and the bellows 74 has contracted further to bring

lever 80 and block 90 to their FIG. 4 positions, then registration of either of the recesses 119a, or 119b with the cam follower portion 111b will result in initiation of a defrost cycle. It will be recognized that the control device 26 provides for the initiation of a deice cycle when predetermined icing temperature and time conditions exist simultaneously, and that the deice cycle is terminated in response to a predetermined high temperature condition.

The control device 26 of this invention provides for positive termination of the deice cycle in the event of a failure of the temperature responsive means, for example if leakage of the fluid therefrom permits the bellows 74 to collapse. Thus, if the deice cycle has not been terminated by the temperature responsive means within a predetermined time interval, the lever 111 is rotated in a counterclockwise direction by the cam 110 as the cam follower portion 111b rides from the relatively low surface 118a or 118b to a higher surface 117b or 117a, respectively. Thereafter, the initiation and termination of the deice cycle will be effected solely on a time basis.

Under some operating conditions, such as prevailing high humidity, it is desirable to provide more frequent deicing cycles than when operating under drier conditions. Accordingly, the control device 26 contemplates the inclusion of means for alternatively masking or unmasking one of the recesses (119b) in the periphery of the cam 110, whereby the device 26 may be selectively conditioned to provide either one or two deicing cycles for each revolution of the cam. To this end, there is provided a mask 135, FIGS. 6, 9, and 10, having a ring portion 135a rotatably mounted on the shaft 121 between a shoulder 136 thereof and a dish-shaped spring washer 137, the peripheral edge of which bears against the gear 126. The spring washer 137 serves as a clutch frictionally holding the mask 135 for rotation with the cam 110, but permitting the mask to be forcibly rotated with respect to the cam from the full line position of FIG. 5 to the dotted line position 135' wherein the end of the mask registers with recess 119b to prevent cam follower portion 111b of lever 111 from dropping into that recess upon rotation of the cam 110.

The rotation of the mask 135 with respect to the cam 110 is conveniently effected through the agency of a sleeve 140 surrounding the shaft 121 and having a recess 141 receiving a tab 135b which extends from the mask ring 135a through an arcuate opening 142 in the cam ring 110. The sleeve 140 projects through, and is journaled in the frame side wall 41a. It will be seen that rotation of the sleeve 140 about the shaft 121 can effect swinging movement of the mask 135 through an arc of approximately 90° as determined by arcuate slot 142 in cam 110 for masking and unmasking recess 119b. The cam 110 and shaft 121 are prevented from turning during movement of the mask 135 by engagement of the gear 126 with pinion 131 which is driven by the motor through reduction gearing having such a ratio as to preclude overrunning. The sleeve 140 is conveniently provided with index marks, for example the numerals 1 and 2 shown on the sleeve in FIG. 1, which may be aligned with a screw driver slot 121a in shaft 121 to select one or two timed periods, respectively, per revolution of cam 110.

From the foregoing detailed description of my invention, it will be appreciated that there has been provided thereby an improved and particularly effective deice control which is responsive to both time and temperature to control deice cycles of a refrigerating system.

Although the invention has been described in considerable detail with reference to a specific deice control embodying the invention, it will be understood that the invention is not limited thereto, but rather the invention includes all those modifications, substitutions, adaptations and uses as are reasonably embraced by the scope of the claims hereof.

Having described our invention, we claim:

1. In a control mechanism for heat pumps and the like, an electric snap switch mechanism having an actuator arm movable between two switch operative positions, means continually urging said arm towards a single one of said positions, a first blocking means movable into and out of the path of movement of said arm to block movement toward said one position, thermally responsive means to move said blocking means into and out of said path, a second blocking means movable along said path of movement of said arm and adapted to be engaged by said arm and separable therefrom when said arm is blocked by said first blocking means, and timer driven cam means for moving said second blocking means in opposite directions along said path of movement.

2. A control mechanism as defined in claim 1 further characterized by said control mechanism including a housing in which said switch, first and second blocking means and cam operated timer are enclosed, and said second blocking means comprising a leaf spring supported in said housing and engaged by said arm and adapted to be flexed by said cam means to move said arm towards said second position.

3. A control mechanism as set forth in claim 1 further characterized by said actuator arm being L-shaped and having portions arranged at substantial right angles to one another, one of said portions being engageable by said first mentioned blocking means and the other of said portions normally engaging said second blocking means.

4. In a control mechanism for heat pumps and the like, an electric snap switch mechanism having an actuator arm movable between two switch operative positions, means continually urging said arm toward one of said positions, a first blocking means movable into and out of the path of movement of said arm to block movement toward said one position, thermally responsive means comprising a first lever supporting said first blocking means, an expansible element for moving said lever in a direction to position said first blocking means in said path of movement of said actuating arm by expansion of said element, said first lever moving in the opposite direction in response to contraction of said element, a second lever engageable by said first lever during movement thereof to move said blocking means in the path of said arm, spring means loading said second lever to resist movement thereof by said first lever, means to limit travel of said second lever in the direction said first lever moves in response to contraction of said element, a second blocking means movable along said path of movement of said arm and adapted to be engaged by said arm and separable therefrom when said arm is blocked by said first blocking means, and timer driven cam means for moving said second blocking means in opposite directions along said path of movement.

5. In a control mechanism for heat pumps and the like, an electric snap switch mechanism having an actuator arm movable between two switch operative positions, means continually urging said arm toward one of said positions, a first blocking means movable into and out of the path of movement of said arm to block movement toward said one position, thermally responsive means to move said blocking means into and out of said path, a second blocking means movable along said path of movement of said arm and adapted to be engaged by said arm and separable therefrom when said arm is blocked by said first blocking means, timer driven cam means for moving said second blocking means in opposite directions along said path of movement, a housing in which said switch, first and second blocking means and cam operated timer are enclosed, said second blocking means comprising a leaf spring supported in said housing and engaged by said arm and adapted to be flexed by said cam means to move said arm toward said second position, 75 said cam means comprising a disc rotatable on an axis

normal to the direction of movement of said actuator arm and having a periphery of irregular diameter for controlling the movement of said leaf spring in opposite directions along said path of movement of said actuator arm, and means to alter the effective diameter of said cam.
